UNITED STATES PATENT OFFICE

2,335,319

GUN

William Summerbell, Watervliet, N. Y.

Application July 13, 1939, Serial No. 284,256

4 Claims. (Cl. 89—2)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a gun and more particularly it has reference to a gun of the type shown in U. S. Patent No. 1,144,285 of June 22, 1915.

In the gun of the patent, a breech block operating on the blow-back principle advances a cartridge into the chamber of the gun barrel and fires the cartridge before it is in its final position so that gas pressure is first utilized to arrest the forward motion of the breech block before acting to drive it rearwardly in recoil. Because a portion of the gas pressure is utilized to arrest the forward motion of the block a relatively light spring may be used to check the recoil motion of the block under influence of the remaining gas pressure. A relatively slow counterrecoil motion of the block is incident to the employment of the relatively light spring and the rate of fire is consequently reduced. Furthermore, because of the dependence on gas pressure to arrest the forwardly moving block it is necessary, in the event of a hangfire, to provide some means for preventing rebound of the block after striking the rear face of the barrel.

In the gun of this invention the breech block is of the same type as that disclosed in the patent but provision is made for a more rapid counterrecoil stroke and for firing from a fixed position just out of battery. This is accomplished by employing a relatively heavy counterrecoil spring and by associating therewith an hydraulic throttling or buffer mechanism.

The specific nature of the invention as well as other objects and advantages thereof will clearly appear from a description of a preferred embodiment as shown in the accompanying drawing in which:

Fig. 1 is a plan view with parts removed of a gun constructed in accordance with the invention.

Fig. 2 is an enlarged sectional view on the line 2—2 of Fig. 1.

Fig. 3 is an enlarged sectional view through the yoke.

Referring to the drawing by characters of reference there is shown a frame A carrying a fixed barrel B and a reciprocable breech block C.

The breech block is provided with a cross-piece 4 projecting laterally through the frame A and each end is attached by means of a pin 5 to a forwardly extending rod 6 which is spaced from the barrel. The front extremities of the rods 6

are similarly attached by pins 7 to a yoke 8 which is slidably mounted on a sleeve 9 fixed on the barrel near its muzzle. The yoke is maintained against rotation by means of pins 9a whose inner ends ride in longitudinal grooves 10 in the sleeve.

A retaining ring 11 threaded on the rear end of the yoke internally carries a nut 12 and a flange 13 confining a collar 14 on the nut so that the nut is freely rotatable when a tool is applied to apertures 15 in the nut. The nut is threaded on a tubular spring seat 16 which has an internal flange 17 on its front end slidably engaging the barrel. The spring seat is constrained to a reciprocating movement by means of screws 18 whose inner ends ride in flutes 19 in the barrel which are in continuation of the grooves 10 in the sleeve 9.

A spring 20 surrounding the barrel is confined between the flange 17 of the seat 16 and an annular shoulder 21 which is provided on the barrel which is located at the front end of the frame. The spring normally holds the breech block in the closed or "in battery" position. The initial loading of the spring may be varied by displacing the spring seat 16 longitudinally of the gun through rotation of the nut 12.

A pair of longitudinally spaced yokes 22—23 attached to the barrel B carry a pair of cylinders 23—23 on opposite sides of the gun and in axial alignment with the rods 6—6. The opposite ends 24—24 of each cylinder are in the form of a stuffing box including packing 25 and a gland 26. Within the front end of each cylinder and immediately in rear of the corresponding end there is provided a bushing 27 which is threaded in place. The bushing which constitutes a valve case is formed with a plurality of longitudinally extending passages 28 which establish fluid communication to the spaces in front and in rear of the bushing. The bushing is also formed with a central, enlarged, cylindrical opening 29 for receiving a piston valve 30 whose stem 31 receives and is threaded to the rod 6. The rod 6 preferably consists of two members 7a and 7b to facilitate assembly and adjustment and the adjacent ends of the two rod members are threaded for attachment with the valve stem.

The rear end of the valve stem 31 is threaded to receive an adjusting nut 32 which constitutes a seat for a helical spring 33. The front end of the spring acts on a valve 34 which is slidably mounted on the valve stem 31 and has a beveled edge which engages a correspondingly shaped seat in the piston valve 30 to close a plurality of passages 37 in the valve 30.

1 the normal position of the parts as shown in
 2 the valves 30 and 34 are both closed and
 3 cylinder is filled with a liquid such as oil. In
 4 position the breech block is in battery.
 5 upon retraction of the breech block the rods 6
 6 moved rearwardly to retract the yoke 8 and
 7 press the spring 20. During the initial move-
 8 ment of the rods the piston valve 30 moves against
 9 liquid in rear of the bushing 27 and throttles
 10 through the passages 28. The liquid acting on
 11 valve 34 maintains it in closed position.
 12 The breech block is returned into battery at a
 13 speed by the spring 20. During the final
 14 portion of the counterrecoil stroke the piston
 15 valve 30 enters the opening 29 in the bushing and
 16 allows the liquid through the passages 28. The
 17 liquid in front of the piston valve is also forced
 18 through the passages 37 therein and opens the
 19 valve 34 which under the influence of its spring
 20 controls the rate of flow of the liquid. In this
 21 manner the final movement of the counter-
 22 recoil breech block is gradually checked and ter-
 23 mated. The gun is fired from a fixed position
 24 out of battery.

claim:

In a gun, a frame, a barrel fixed to the
 frame, a breech block slidably mounted in the
 frame, a counterrecoil mechanism for the block
 including a forwardly extending rod, a cylinder
 containing a liquid fixed to the barrel and axially
 mounting the rod, a valve case within the cylinder
 and having a central opening and a plurality of
 longitudinal throttling passages, a piston valve
 having a stem carried by the rod and movable
 through the central opening of the valve case, said
 piston valve formed with a beveled valve seat
 and passages, a valve slidable on the stem
 of the piston valve and having a beveled face
 facing the beveled seat of the piston valve to
 close the passages therein, and a spring for said
 closed valve.

In a gun having a barrel, a recoil and

counterrecoil buffer mechanism comprising a
 cylinder stationary with said barrel containing
 a fluid and including a valve case having a
 central opening and longitudinal throttling
 passages, a piston valve adapted to move into
 and out of the central opening of the valve case,
 a pair of rods inserted through the opposite ends
 of the cylinder and threaded to the piston valve,
 an opening in said valve and a spring pressed
 closure therefor, and a spring connected to said
 rods to urge the same in counterrecoil, said clo-
 sure positioned to yield to passage of the fluid
 during counterrecoil of the rods.

3. In a gun, a frame, a barrel fixed to the
 frame, a breech block slidably mounted on the
 frame, a counter-recoil mechanism comprising a
 forwardly extending rod connected to the breech
 block, a cylinder having front and rear chambers
 and containing a fluid, said cylinder being fixed
 to the frame and containing the rod, a bushing
 fixed in the cylinder and having fluid passages
 therethrough establishing communication be-
 tween the chambers and having an enlarged
 central opening, a piston in said opening having
 a fluid passage therethrough and a valve seat
 thereon, said piston being fixed to the rod, a
 valve cooperating with said valve seat control-
 ling the passage of fluid through the piston, and
 a counter-recoil spring normally seating said
 valve.

4. In a gun, a frame, a barrel fixed to the
 frame, a breech block slidable in the frame, a
 pair of forwardly extending rods connected to
 the breech block, a sleeve fixed to the barrel,
 a yoke slidable on the sleeve and connected to
 the rods, a spring seat adjustably carried by the
 yoke, a spring surrounding the barrel and con-
 fined between the spring seat and the rear part
 of the barrel, and guideways in said sleeve and
 means on the spring seat coacting with said
 guideways to prevent rotation of the spring seat.

WILLIAM SUMMERBELL.
